(57) **CLAIM**

The ornamental design for a crystal table lamp, as shown and described.

DESCRIPTION

FIG. 1 is a front perspective view and top perspective view of a crystal table lamp, showing the first embodiment of my new design;

FIG. 2 is a rear perspective view and bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front perspective view and top perspective view of a crystal table lamp, showing the second embodiment of my new design;

FIG. 10 is a rear perspective view and bottom perspective view thereof;

FIG. 11 is a front elevational view thereof;

FIG. 12 is a rear elevational view thereof;

FIG. 13 is a left side view thereof;

FIG. 14 is a right side view thereof;

FIG. 15 is a top plan view thereof; and,

FIG. 16 is a bottom plan view thereof.

The broken lines in the figures are for the purposes of illustrating portions of the crystal table lamp, which form no part of the claimed design.
